UNITED STATES PATENT OFFICE.

CHARLES WILLIAM McDANIEL, OF LAKE VILLAGE, NEW HAMPSHIRE.

DRILLING-MACHINE.

SPECIFICATION forming part of Letters Patent No. 410,803, dated September 10, 1889.

Application filed June 21, 1888. Serial No. 277,707. (No model.)

To all whom it may concern:

Be it known that I, CHARLES WILLIAM McDANIEL, a citizen of the United States, residing at Lake Village, in the county of Belknap 5 and State of New Hampshire, have invented a new and useful Improvement in Drilling-Machines, of which the following is a specification.

My invention relates to an improvement in 10 drilling-machines; and it consists in the peculiar construction and combination of devices that will be more fully set forth hereinafter, and particularly pointed out in the claims.

The object of my invention is to provide a 15 drilling-machine which is adapted to drill a hole either vertically, horizontally, or at any desired intermediate angle, and in which the drill-rod may be either fed automatically to its work or by hand-power.

20 In the accompanying drawings, Figure 1 is a perspective view of a drilling-machine embodying my improvement. Fig. 2 is a vertical sectional view of the same. Fig. 3 is a horizontal sectional view taken on the line *x x* of Fig. 1. Figs. 4 and 5 are detail views. Fig. 6 is a detail view, partly in section, on the line *a a* of Fig. 2.

25 A represents the bed-plate, which is of the usual construction, and B represents a vertical cylindrical standard, which is secured to the bed-plate near one end thereof and rises therefrom.

30 Formed on the upper side of the bed-plate, arranged concentrically with the standard, is a circular boss or offset C, and the lower portion of the standard is reduced for a suitable length to form a spindle D.

35 E represents a horizontal bracket-arm, which has one end pivoted on the spindle D, and is 40 adapted to move vertically thereon. The said arm is made of two longitudinal pieces F, which are bolted together, and one of which is provided with a pair of ears G.

45 A rack-bar H is arranged in a vertical position and bears against one side of the spindle, has its lower end guided in an annular recess I in the offset C, and said rack-bar extends between the ears G. A shaft K is journaled transversely in the said ears, and is provided with a spur-wheel L, which meshes with the rack-bar, and has a ratchet-wheel M at

one end, which is engaged by a pawl N, that is pivoted to the inner end of arm E.

A pair of transverse openings O is made through the projecting portion of the shaft L 55 on the inner side of the ratchet-wheel, which openings are adapted for the insertion of a pinch-bar or lever, by means of which the shaft may be rotated, so as to cause the rack and pinion to raise or lower the arm on the 60 spindle. The function of the pawl is to secure the arm at any desired vertical adjustment. Inasmuch as the rack-bar bears loosely 65 against the spindle, and is secured in the arm E, which is pivoted on the spindle, it follows 70 that the said arm may be turned in a horizontal direction to any desired position.

P represents the drill plate or table, which is circular, as shown, has a series of radial slots R, and is provided at its center with a 75 depending spindle S, which is journaled in a vertical opening in the outer end of arm E, thereby enabling the plate or table to be revolved on the said arm. The length of the pivotal spindle is such that it enables the 80 table or plate to be adjusted vertically a slight distance upon the arm, and at the outer end of the arm E is a set-screw T, which is adapted to impinge against the spindle, so as to secure the plate or table in any desired position.

In the center of the plate or table and extending through the center of the spindle is a vertical bore U. In the upper end of the said standard is a horizontal opening V, and on the front side of the standard and concentric 85 with the said opening is a circular face W, Fig. 1, which has a concentric annular groove X, Fig. 2, that is T-shaped in cross-section. A vertical slot Y, which is also T-shaped in cross-section, communicates with the upper 90 side of the groove X and is open at its upper end, as shown.

Z represents the drill head or frame, which comprises the horizontal arms A'B', connected at one end by a vertical arm C'. At the upper corner of the frame or head is formed a circular disk D', the diameter of which is equal to the diameter of the face W, and projecting from the center of the said disk is a hollow cylindrical sleeve E', which is journaled in the opening V, and thereby pivots the drill-head to the standard. The outer end

of the sleeve, which projects beyond the rear side of the standard, is screw-threaded, and a clamping-nut F' is screwed thereon, the function of which is to cause the disk to bear 5 snugly against the face W.

G' represents a pair of bolts, which have T-shaped heads fitted in the annular groove X and arranged at diametrically-opposite points, and the shanks of said bolts extend forward 10 through the diametrically-opposite openings in the disk T', and are provided with clamping-nuts H'. By means of the said bolts and clamping-nuts the disk D' may be clamped firmly to the face when in a vertical, horizontal, or any other desired position, thereby 15 adapting the machine to drill holes at any desired angle, as will be readily understood. The groove Y, which communicates with the groove X, enables the bolts G' to be inserted 20 in or removed from the latter groove when the machine is being assembled or disassembled.

I' represents a vertical hollow cylindrical sleeve, which is arranged in a vertical opening 25 at the outer end of the arm B', and is adapted to move in a vertical direction in the said arm. On the inner side of the said sleeve is secured a rack-bar K', which works in a vertical longitudinal slot L', with which the 30 arm B' is provided.

M' represents a transverse shaft, which is journaled in a horizontal opening that is made in the arm B' and intersects the slot L'. Fitted in the said slot and feathered on 35 the said shaft is a pinion N', which meshes with the rack K'.

O' represents a worm-wheel, which is loosely journaled on the shaft M', and is secured against longitudinal movement on the 40 shaft by means of a key P', that extends through the shaft, and has one end projecting beyond the same and arranged in a concaved recess R in the outer side of the worm-wheel. The extremities of the shaft are provided with screw-threads. A loose washer 45 O' bears between the worm-wheel and arm B'. S' represents a wheel or disk, which is mounted on the shaft M' and is feathered thereto by means of the key P'. On the inner side of the said disk or wheel is formed 50 a concentric offset T', which fits in the recess R' of the worm-wheel.

From the outer side of the wheel or disk S' projects a crank-handle U', Fig. 3, and a 55 nut V' is screwed to the projecting end of the shaft M' and bears against the outer side of the wheel or disk. To the opposite end of the said shaft M' is screwed a clamping-nut W', the function of which is to prevent longitudinal 60 motion of the shaft in its bearings.

Secured to the under side of the arm B' and arranged at right angles thereto is a bracket X', Fig. 3, in one end of which is swiveled a shaft Y', that has a worm Z' formed 65 at one end which engages the worm-wheel, and has a miter-wheel A' keyed to its inner end.

B², Fig. 1, represents a pair of ears or brackets which project from one side of the vertical arm C' of the frame or head. A vertical shaft C² is journaled in the said ears, has a cone-pulley D² secured near its upper end, and is provided near its lower end with a miter-wheel E², which meshes with the wheel A², Fig. 3. 70

F² represents the drill-shaft, which is swiveled in the sleeve I', and has its upper portion journaled in a vertical opening in the outer end of the arm A'. The lower end of the said shaft is enlarged to form a head and 80 is provided with a vertical central tapered opening or socket to receive the tapered upper end of the shank of the drill. 75

G² represents a collar, which is secured to the drill-shaft by means of a set-screw and 85 bears against the upper end of the sleeve I', the drill-shaft being thereby prevented from moving vertically independently of the said sleeve.

H² represents a hollow sleeve, which is feathered on the upper portion of the drill-shaft and is journaled in the outer end of the arm A'. Formed with the upper end of the said sleeve is a miter-wheel I², and formed with or 90 secured to the lower end of the said sleeve is 95 a series of pulleys K², which align, respectively, with the cone-pulley, Fig. 1.

L², Fig. 1, represents the driving-shaft, which is journaled in the sleeve E' and in a bearing formed on the upper side of the arm A'. To the outer end of the said shaft is keyed a miter-wheel M², which meshes with the wheel I², and to the said shaft is keyed a spur-wheel N². The said spur-wheel is provided in one side, near its perimeter, with an 100 opening O². 105

P² represents a driving cone-pulley, which is loosely mounted on the shaft L², bears against the wheel N², and has a pinion R² at its smaller end. 110

S², Fig. 1, represents a screw which is adapted to pass through the opening O² and to engage the threaded opening in the larger end of the cone-pulley, so as to secure the latter to the wheel N², for the purpose to be 115 hereinafter described.

Secured to the outer side of the standard B is a bracket T², having a vertical arm U² at its outer end. An eccentric-shaft V² is journaled in the said arm U² and in the standard 120 B, and has a crank W² at its outer end, by means of which it may be turned.

X² represents a tubular sleeve, which is journaled on the eccentric-shaft and is provided at one end with a spur-wheel Y², and 125 has a pinion Z² at the opposite end.

The operation of my invention is as follows: Power is applied to the driving-shaft by means of an endless belt, which engages the cone-pulley P² and receives its motion 130 from the pulley on a suitable counter-shaft. (Not shown.) The miter-wheels, which connect the driving-shaft to the drill-shaft, communicate rotary motion to the latter, and the

pulleys on the sleeve at the upper end of the drill-shaft being connected to the cone-pulley on the shaft C² by means of an endless belt rotary motion is also imparted to the said shaft C². When it is desired that the drill shall be fed automatically, the nut on the threaded end of the shaft M' is tightened, so as to cause the wheel or disk S' to be so firmly forced against the outer side 5 of the worm-wheel as to lock the latter fast to the said disk. Inasmuch as the disk is feathered to the shaft it will be understood that when the worm-wheel is thus locked to the disk it cannot rotate independently of the shaft M'; hence, being connected to the shaft C² by the worm and miter wheels, said worm-wheel, disk, and shaft M' are caused to rotate slowly, and the pinion N', which is secured to the shaft M', being in engagement 10 with the rack on the inner side of the sleeve in which the lower end of the drill-shaft is swiveled, lowers the said sleeve and said drill-shaft slowly, and thereby feeds the drill automatically to its work, which is placed on the 15 table or disk P in the usual manner.

In order to feed the drill by hand it is only necessary to turn the nut on the end of the shaft M', so as to cause the worm-wheel to become disengaged from the shaft M', so that 20 the latter may be rotated independently of the worm-wheel, and the operator then grasps the crank on the wheel or disk S', and by means of the same rotates the shaft M', so as to feed or withdraw the drill, as may be desired.

The counter-shaft (not shown) by which the cone-pulley P² is driven is run at a uniform speed at all times, and when the said cone-pulley is secured to the wheel N² by the screw 25 O² the eccentric-shaft must be turned so as to cause the wheels Y² Z² to become disengaged from the wheels R² and N², and the shaft L² is rotated at maximum speed, the sleeve and wheels on the eccentric-shaft being not in motion. In order to reduce the speed of the 30 shaft L² to the minimum extent, the screw O² is withdrawn so as to disconnect the cone-pulley from the wheel N², and the eccentric-shaft is turned so as to cause the wheels Y² Z² 35 to become engaged with the wheels R² and N², respectively. When thus arranged, the cone-pulley rotates independently of the shaft L², the pinion R², being of less diameter than wheel Y², causes the sleeve X² to rotate at a 40 slower rate of speed than the cone-pulley, and the pinion Z², being of less diameter than the wheel N², which is rigid with the shaft L², causes said wheel N², and consequently the 45 said shaft, to be rotated still more slowly, as will be very readily understood.

On the perimeter of the circular disk D' is inscribed a graduated scale indicating the degrees of a circle, and this scale moves with reference to a fixed point on the perimeter 50 on the face W when the drill head or frame is turned, and facilitates the ar-

angement of the drill-shaft at any desired angle.

Having thus described my invention, I claim—

1. The combination of the drill-head, the sleeves journaled therein, one of said sleeves having the pulleys and being geared to the driving-shaft and the other sleeve having the rack-bar, the drill-shaft feathered in the upper sleeve and swiveled in the lower sleeve, the shaft M', having the pinion engaging the rack, the worm-wheel loose on the said shaft, the worm engaging said worm-wheel, the shaft C², geared to the worm and having the 70 pulley connected to the pulley on the upper sleeve by an endless belt, the disk S', feathered on shaft M', and the nut V' on said shaft to compress the disk S' against the worm-wheel and to release the latter from the disk, whereby the drill may be fed either automatically or by hand, substantially as described.

2. In a drilling-machine, the drill-head F, the sleeves journaled thereon, the upper 90 sleeve having the pulley K², the driving-shaft L², geared to the upper sleeve, the lower sleeve having the rack-bar, the drill-shaft F², feathered in the upper sleeve and swiveled in the lower sleeve, the shaft C², having the pulley D², the belt-connections between the pulleys D² and K², the pinion N', engaging the rack-bar on the lower sleeve, the shaft M', carrying the pinion, the shaft Y', geared to shaft M', and the gearing connecting the shafts Y' and C², as set forth.

3. In a drilling-machine, the drill-head Z, the sleeves H² I', journaled therein, the upper sleeve H² having the gear I² and the pulley K², and the lower sleeve I' having the 105 rack K', the drill-shaft F², feathered to the sleeve H² and swiveled in the lower sleeve I', the driving-shaft L², having a gear meshing with the gear I², the shaft C², having a pulley D², connected to the pulley K², the pinion N', meshing with the rack K', the shaft M', for the pinion, worm-wheel O', on the shaft, worm Z', engaging the worm-wheel, the shaft Y', for the worm, and the gears A² E², connecting shafts Y' and C², as set forth.

4. In a drilling-machine, the drill-head Z, having disk D', the standard B, having the face W, the diameter of which is equal to the diameter of the disk D', the sleeve E', projecting from the disk and journaled in a 120 horizontal opening V of the standard, the clamping-nut F for the sleeve E', the concentric annular groove X, made in the face W, the vertical slot Y', also made in the face and communicating with the groove X, 125 the bolts G', having their heads in the groove X, the nuts H' for the bolts, and the drill mechanism carried by the drill-head, whereby drilling at an angle can be performed, as set forth.

5. The combination, in a drilling-machine, 130 of the vertically-movable sleeve I', having

rack K', the drill-shaft swiveled in said sleeve, the sleeve H², having pulley K², the shaft M', having the pinion engaging rack K', the worm-wheel O', loose on said shaft, the shaft 5 having the worm engaging the worm-wheel, the shaft C², geared to the worm-shaft and having the pulley D², connected to pulley K², the disk S', feathered on the shaft M' and having the crank U', and the nut V' on said 10 shaft, adapted to engage the said disk with

the worm-wheel and to disengage the same therefrom, substantially as described.

In testimony that I claim the foregoing as my own I have hereto affixed my signature in presence of two witnesses.

CHARLES WILLIAM McDANIEL.
